UNITED STATES PATENT OFFICE.

JULIA A. ROBINSON, OF MANCHESTER, IOWA.

CLOTHES-PROP HOLDER.

1,276,571.

Specification of Letters Patent. Patented Aug. 20, 1918.

Application filed January 10, 1918. Serial No. 211,206.

To all whom it may concern:

Be it known that I, JULIA A. ROBINSON, a citizen of the United States, residing at Manchester, in the county of Delaware and 5 State of Iowa, have invented new and useful Improvements in Clothes-Prop Holders, of which the following is a specification.

This invention has reference generally to improvements in that class of inventions 10 known as laundry, and more particularly relates to a clothes prop holder.

It is the principal aim and object of the present invention to provide a device of the above mentioned character designed for engagement with a clothes line, and capable of receiving one end of a prop, so as to coöperate with the latter in preventing the accidental falling of the prop, consequently assuring the maintenance of the clothes line 15 in an elevated position.

More particularly, the invention includes the provision of a device of the above mentioned character wherein improved means are employed for removably clamping the 20 sections of the holder and opposite sides of the line.

It is a more specific object of this invention to provide a device of the above character wherein the construction thereof is 25 novel and is capable of being readily applied and maintained in position when in use.

It is a more specific object of this invention to provide a clothes prop holder of 30 the character mentioned, wherein improved means is employed for engaging the line, while coöoperating therewith is improved guard means for preventing unnecessary movement of the device when in position on 35 the line.

Among the other aims and objects of this invention may be recited the provision of a device of the character described with a view to compactness, and in which the number 40 of parts are few, the construction simple, the cost of production low and the efficiency high.

Other improvements and novel details in the construction and arrangement of the 45 various parts of the apparatus will be brought out more in detail in the description to follow, which for a clear understanding of the invention should be considered in connection with the accompanying 55 drawings forming a part hereof, and where-

in is disclosed for the purpose of illustration a convenient and satisfactory embodiment of the invention. It is to be noted in this connection that minor changes in the construction and arrangement of parts may 60 be made without departing from the principle of operation of the various parts.

The invention is clearly illustrated in the accompanying drawings, in which:

Figure 1 is a side elevation of the invention 65 positioned on a clothes line, the latter being shown in section.

Fig. 2 is a longitudinal section of the same.

Fig. 3 is a front elevation of the invention. 70

Fig. 4 is a top plan view thereof.

Similar characters of reference are employed in all of the above described views to indicate corresponding parts.

Referring now, more particularly, to the 75 accompanying drawings, there is provided a pair of sections or plates 1 and 2, which may be and preferably are formed of metal, the lower ends of each of which are formed with hinged ears 3 which are engaged by a 80 pintle 4 which serves to connect the sections so that they may be swung relative to each other. Extending at right angles from the opposite side edges of the plates 1 and projecting toward the other plate are a pair of 85 opposed hooks 5, while positioned above the hooks and at right angles to and integral with the same plate or section 1 are opposed guards 6. The hooks and guards are designed to be arranged in close relation upon 90 the opposite side of the other plate 2 when the latter is swung toward the plate 1, while preparatory to this swinging movement the hooks are engaged beneath a clothes line 7.

In order to removably retain the sections 95 in the relation described and prevent accidental displacement thereof, an adjusting screw 8 is engaged through the extensions 9 or on the upper ends of the plates 1 and 2.

Clothes prop receivers 10 are connected 100 on the outer surfaces of the sections or plates 1 and 2 and preferably include a triangular outer wall 11, inclined side walls 12, which are joined with the top 13. The bottom or lower ends of these receivers are 105 open, while attaching flanges 14 are formed on the side walls and are secured to the sections or plates 1 through the instrumentality of suitable fasteners 15. Subsequent to the engaging of the hooks 5 on the line, 110

7 and the swinging of the sections or plates 1 and 2 toward each other and the fastening of the adjusting screw 8, the clothes props 16 have their upper ends engaged in 5 the receivers 10 so as to coöperate with the hooks 5 in maintaining the clothes line 7 in an elevated position. It is appreciated, of course, that the guards 6 prevent the accidental unnecessary movement of the line 10 when between the plates or sections. In disconnecting the device it is only necessary to remove the props and unloosen the screws 8 so that the sections may be swung away 15 from each other and the hooks 5 disengaged from the line, as is apparent.

It is thought in view of the foregoing description that a further detailed description of the operation of the invention is entirely unnecessary. Likewise it is believed 20 that the advantages of the invention will be readily apparent.

As many changes could be made in the above construction and many apparently widely different embodiments of this invention could be made without departing from the scope of the invention, it is intended 25 that all matter contained in the above description or shown in the accompanying drawings shall be interpreted as illustrative 30 and not in a limited sense. It is also to be understood that the language used in the following claims is intended to cover all the generic and specific features of the invention herein described and all statements of the

scope of the invention which as a matter of 35 language might be said to fall therebetween.

Having thus fully described this invention, what is claimed as new and desired to be secured by Letters-Patent, is:—

1. A device of the character described in 40 including a pair of plates swingingly connected to each other at their lower edges, opposed hooks projecting at right angles from the inner surface and adjacent side edges of one of the plates, opposed guards 45 formed with the same plate and positioned above the hooks, means for removably holding the upper ends of the plates in close relation with each other, and clothes prop receivers carried on the outer surfaces of 50 the plates.

2. A device of the character described in 55 including a pair of plates having lower edges swingingly connected to each other, opposed clothes line engaging hooks projecting at right angles from the inner surface of one 60 of the plates and at the side edges thereof, opposed guards extending from and integral with the same plate and positioned above the hooks, an adjusting screw for removably holding the upper ends of the plates in close relation with each other, and clothes prop receivers carried on the outer surfaces of the plates and opening toward 65 the lower edges of the plates.

In testimony whereof I affix my signature.

JULIA A. ROBINSON.
